UNITED STATES PATENT OFFICE.

HENRY ALLENDER, OF DETROIT, MICHIGAN.

MECHANISM FOR DRIVING GAS-MACHINES.

SPECIFICATION forming part of Letters Patent No. 366,061; dated July 5, 1887.

Application filed April 1, 1887. Serial No. 233,330. (No model.)

To all whom it may concern:

Be it known that I, HENRY ALLENDER, of Detroit, in the county of Wayne and State of Michigan, have invented a new and useful

5 Improvement in Mechanism for Driving Gas-Machines, of which the following is a specification.

My invention consists in an improved mechanism for driving gas-machines, &c., herein-
10 after fully described.

The drawing is an elevation.

18 represents the shell of the air-pump of a gas-machine, while 14 represents the pump driving-shaft, and 13 a pinion on said shaft.

15 10 represents a shaft journaled in hanger 19, which is secured to any convenient point of support, usually a joist in the ceiling of the room in which the air-pump is placed, and carries a sprocket-wheel, 8, and pinion 9, se-
20 cured together.

25 6 represents a shaft journaled in hanger 20, supported similarly to hanger 19, and carrying a gear-wheel, 7, which meshes with pinion 9, and a sprocket-wheel, 5, both secured and rotating together.

20 21 represents a shaft journaled in a hanger, 3, secured at a little distance from hanger 20, carrying thereon a sprocket-wheel, 1, and a ratchet-wheel, 2, both secured together.

30 30 4 represents a pawl pivoted to hanger 3, and engaging with ratchet-wheel 2, so that said ratchet-wheel and wheel 1 can turn only in one direction.

35 11 represents an endless chain which connects sprocket-wheel 8 and sprocket-wheel 13, so that the motion of said wheel 8 is communicated to said wheel 13.

22 represents an endless chain of consider-
able length, which runs over wheels 1 and 5,
40 and 15 represents a driving-weight which is hung by a pulley, 16, on that part of chain 22 (marked 17) which lies between wheels 1 and 5, whereby said weight tends to rotate said wheel 5, and thereby, through wheel 7, pinion 9, wheel 8, chain 11, and wheel 13, to rotate

45 the driving-shaft 14 of the air-pump 18. I prefer to use chains rather than ropes or belts, though either of these may be substituted, and wheels 13, 5, 8, and 1 may be of any kind that
50 will not permit the chain, rope, or belt, which-ever is used, to slip.

In the drawing I have illustrated these

wheels as sprocket-wheels; but any known form of wheel adapted to be used with the transmitting medium employed may be substituted.

As gas-machines are at present built, the driving-shaft of the air-pump has thereon a spool, round which a rope is wound, and said rope is usually run through suspended multi-
60 ple pulleys, to the lower one of which is hung the driving-weight. This construction necessi-tates a long extension of the driving-shaft of the air-pump, causes the rope to wear because it runs at an angle from the ends of the spool 65 to the pulley, and necessitates the introduction of mechanism to keep the pump in motion during the operation of winding up the driving-wheel.

The operation of my invention is as follows: 70 As the shaft of the air-pump is driven by an endless belt or chain, the wheel 13 can be placed close to the shell of the pump, thus doing away with the long extension of the driving-shaft. When the weight 15 descends, 75 so that it is necessary to wind it up, this is done by pulling down on the right-hand part of the lowest bight of the chain 22, which causes wheel 1 to rotate in the direction permitted by the pawl 4, and raises the weight 80 without at any time interfering with its action on wheel 5, and the instant the winding operation ceases pawl 4 prevents reverse rotation of wheel 1, and the weight 15 can only descend as fast as is necessary to drive the 85 pump.

What I claim as my invention, and desire to secure by Letters Patent, is—

1. In combination with two hangers, each carrying a shaft, on one of which is journaled 90 a wheel, 1, and a ratchet-wheel, 2, controlled by a pawl, 4, and on the other of which are journaled wheels 7 and 5, an endless chain passing over one of the wheels on each of said shafts, and a driving-weight on said endless 95 chain between said shafts, substantially as shown and described.

2. In combination with a shaft, 14, and a wheel, 13, secured on said shaft, an endless belt or chain, a counter-shaft, wheel on said 100 counter-shaft, multiplying gear for driving said counter-shaft, and an endless chain passing over a wheel on said counter-shaft and over a wheel provided with a ratchet-wheel

and pawl, and a weight upon the chain between said wheels, substantially as and for the purposes set forth.

3. A driving mechanism consisting of two 5 wheels, one connected by gearing with the shaft to be driven, and the other provided with a pawl and ratchet, an endless chain

passing over said wheels, and a driving weight hung by a pulley from said chain between said wheels, substantially as shown and described. 10

HENRY ALLENDER.
